COMBINED BAR AND SEAT THEREFOR OR SIMILAR ARTICLE

Thomas J. Welter, Belmar, N. J.

Application May 25, 1956, Serial No. 41,654

Term of patent 14 years

Fig. 1

(Cl. D33—14)

Fig. 2

Fig. 3

Fig. 4

Fig. 5

Fig. 6

Figure 1 is a front elevational view of a combined bar and seat therefor or similar article, showing my new design;

Figure 2 is a side elevational view, both sides being the same in appearance;

I claim:

The ornamental design for a combined bar and seat therefor or similar article, as shown.
